REFRIGERATOR

Henry M. Herbener, Thomasville, Ga.

Application May 1, 1943, Serial No. 485,366

30 Claims. (Cl. 62—95)

1

My invention relates to refrigerators, such as are operated by a compressor, heat or the like.

An important object of the invention is to provide refrigerating apparatus having the maximum efficiency.

A further object of the invention is to provide a refrigerator which may be operated intermittently, throughout the entire day, or operated during a portion of the day, when current or the like is cheap or available, which produces ice, which is employed to properly chill the refrigerator, when the ice producing means is inactive.

A further object of the invention is to provide means whereby the liquid freezable medium is frozen in thin layers.

A further object of the invention is to first freeze the liquid freezable medium at the bottom and cause the freezing action to continue upwardly, so that the resultant ice will not burst the container or tank of the liquid freezable medium.

A further object of the invention is to retain the previously formed and partly melted ice when floating, spaced from the freezing device or wall, thus providing a layer of the liquid freezable medium in direct contact with the freezing device or wall, for the next freezing cycle.

A further object of the invention is to provide means to guide the ice produced in the tank when the ice partly melts and floats, so that the ice is retained centered with respect to the tank.

A further object of the invention is to guide the floating ice into thermal contact with the heat transfer wall of the refrigerator casing while retaining the same spaced from the freezing means or wall.

A further object of the invention is to provide means for freezing a liquid freezable medium, having a suitable volume so that the ice produced is employed to retain the perishable products at a suitable refrigerating temperature, for a desired length of time, without liability of dehydrating them.

A further object of the invention is to provide a refrigerator having a large number of thin liquid freezable medium holding tanks, for producing a sufficient volume of ice to properly chill the refrigerator, and permitting of the formation of the ice quickly and economically.

A further object of the invention is to provide a refrigerator having a separate compartment within its casing, which is heat insulated and having means for producing therein a sub-freezing temperature.

A further object of the invention is to provide

means for surrounding the sub-freezing compartment, in whole or in part, with chilled air.

A further object of the invention is to provide a refrigerator of the above mentioned character, wherein a proper circulation of the air is effected.

A further object of the invention is to provide a downwardly tapered tank for holding the liquid freezable medium with an expansion space at its top and means for applying the freezing action to the lower reduced portion of the tank, thereby increasing the efficiency of the apparatus.

A further object of the invention is to freeze the liquid freezable medium within the tank from the bottom toward the top whereby the unfrozen water at the top serves as a shield to prevent the food products being subjected to a sub-freezing temperature.

A further object of the invention is to arrange the thermostatic element at or near the level of the water in the tank so that the compressor will be stopped when the water is completely frozen from the top to the bottom.

A further object of the invention is to provide the wall or walls of the refrigerating casing with liquid freezable medium holding tanks, whereby ice may be produced within such tanks, to retain the interior of the refrigerating casing at a suitable refrigerating temperature without dehydrating the edible food products, and to prevent heat exchange between the interior of the casing and the exterior thereof.

A further object of the invention is to provide a tank so shaped that the top cross section is larger than the bottom cross section to provide extra room for floating ice so that the top cannot freeze over before the bottom of the liquid is frozen.

This application is a continuation in part of my co-pending application for refrigeration apparatus, filed May 7, 1940, Serial No. 333,855.

In the accompanying drawings forming a part of this application and in which like numerals are employed to designate like parts throughout the same.

Figure 15 is a central vertical section through a further modified form of the invention.

Figure 16 is a perspective view of the refrigerant circulating coil, and

Figure 17 is a plan view of the chilled fluid circulating passage.

In the drawings, wherein for the purpose of illustration is shown a preferred embodiment of my invention, the numeral 10 designates a casing, including sides 11, a back 12, a front 13, a top 14 and a bottom 15. The casing includes a lower compartment 16 for receiving the operating mechanism, including a compressor and motor, if this type of mechanism is employed, or a gas burning unit, or other heat operated unit, if the latter type of mechanism is used. The front 13 has the usual main entrance opening covered by a hinged door 17.

The top 14 is double-walled, including an inner wall 18 and an outer wall 19, formed of metal or the like.

Arranged within this double-walled top 14 is refrigerating means 18^a, adjacent to and in thermal contact with the inner wall 18. This refrigerating means is spaced from the outer wall 19, and from the outer walls of the front and back 13 and 12, and is surrounded by heat insulating material 19, arranged outwardly of the same, as shown. The refrigerating means 18^a includes a plurality of horizontal tanks 20, preferably extending transversely of the casing 10. These tanks are hermetically sealed, are elongated, and taper downwardly and are generally V-shaped in cross-section and include downwardly converging sides 21^b. These tanks also include downwardly converging ends 21. The tanks 20 preferably have their tops arranged in thermal contact and their upper ends may be hermetically sealed by a common cover 22. The tanks 20 are separate and are filled for the major portion of their height with a freezable liquid medium, as indicated at 23. This liquid medium may be water, brine, or other liquid having a freezing point below water. The tanks 20 are not completely filled with the freezable liquid medium, as a permanent air space 24 is provided in each tank, which permits of the expansion of the liquid medium, upon freezing. Each tank 20 preferably has a narrow bottom 25. Secured to each bottom

25 and in thermal contact therewith are vertical heat exchange ice guide pins or devices 26. These guide pins are disposed at the central longitudinal axis of the tank, are arranged therein, and are spaced longitudinally of the tank. The guide pins 26 preferably have their upper ends spaced from the plate 22 and preferably terminate at about the elevation of the freezable liquid medium within the tanks. The tanks and associated elements are formed of metal or other suitable heat exchange material. The freezing of the liquid medium within the tank is effected by applying a freezing action to the bottom or lower portion of the tank, and the freezing starts at the bottom of the liquid freezable medium and continues upwardly. This provides an expansion space at the top of the resultant ice so that the tank cannot be bursted by the ice. After the freezing action is discontinued, which usually occurs after all of the liquid freezable medium has been converted into ice, the resultant ice within the tank serves to chill the interior of the casing. Due to the heat exchange action of the inclined walls of the tank and the guide pins, the ice will first melt adjacent to the same. This frees the ice from contact with the tank, so that it may float or rise, and the guide pins serve to retain the floating ice centered in the tank so that the floating ice is spaced from the bottom, side, and end walls of the tank. When the freezing or chilling action is again applied to the lower portion of the tank, with the remaining ice floating in the tank, the ice will be out of the way so that the liquid medium at the bottom and sides of the tank may be quickly and properly frozen, since it will be in a thin layer and in thermal contact with such bottom and sides.

Surrounding the lower portions of the tanks 20 are expansion elements or coils 25', in thermal contact with the lower portions of the sides and ends of the tanks. Each coil extends from the bottom of the sides of the tank 20 and extends through about one half of the vertical dimension of such sides. Portions of the coils 25' are within recesses 26', occurring between the tanks. Since the coils are adjacent to the lower half of the sides of the tank, the freezing occurs first at the bottom of such sides, and quickly, and continues upwardly, and slows down upwardly. The refrigerating means 18^a is arranged within the double-walled top 14, and is disposed between the outer wall 19 of the tank and a compartment A of the refrigerator casing, and will prevent or retard heat exchange from the compartment A to the outer wall 19' of the top, while serving to chill the compartment A.

The back of the refrigerator is double-walled and includes an outer wall 27^a and an inner wall 27. The refrigerating means 28 is mounted within this double-walled back, and includes a vertical group of tanks 29. The wall 27 is common to all the tanks and constitutes the inner vertical walls of the tanks. Each tank 29 further comprises an outer inclined wall 30, secured to the wall 27 and to a top 31. Each tank is hermetically sealed and receives a liquid freezable medium, such as water, brine or the like, partly filling the same, and leaving an air space 33, for expansion, upon freezing. The several tanks are in thermal contact with each other and in thermal contact with the inner wall 27, forming a part thereof, but are spaced from the outer wall 27^a, and heat insulating material 34 is arranged between the tanks 28 and the wall 27^a, as shown. Arranged within each tank are heat ex-

change ice guide pins 35, in thermal contact with the side 30, and spaced from the top 31 and side 21, and extending approximately to the level of the liquid freezable medium therein. If desired, the pins 35 may be in thermal contact with the side 27 or top 31, or both. The guide pins 35 are spaced longitudinally of the tanks, are disposed in transverse vertical planes, and are inclined toward the wall 27. The guide pins 35 correspond to the guide pins 26, and serve to guide the ice as it melts, so that the ice moves from the wall 30 and into thermal contact with the wall 21. The expansion elements or coils 36 are arranged in thermal contact with the lower half of the sides 30 of tanks 29.

Arranged beneath the compartment A is a double-walled shelf 37, supported by the back of the casing and spaced from the sides and front, as shown. This double-walled shelf includes a lower diagonal sheet 38 and an upper horizontal sheet or cover 39. This double-walled shelf receives and holds tanks 40, 41 and 42, similar and corresponding to the tanks 18^a, but differing slightly in shape in transverse section, so that they may be accommodated within the double-walled shelf 37. The tanks 40, 41 and 42 have their bottoms spaced from the diagonal sheet 38 while their tops are in thermal contact with the cover 39. Heat insulating material 43 is arranged within the double-walled bracket 37 and is disposed between the tanks and the inclined sheet 38, as shown. The tanks 40, 41 and 42 are hermetically sealed and the cover 39 is common to them. Each tank is separate but is preferably in thermal contact with the next tank and receives a liquid freezable medium, such as water, brine or the like, partly filling the same, leaving an upper air space. Each tank within the double-walled bracket is provided with an expansion element or coil 44, in thermal contact with the lower half of its sides, and these coils correspond to the expansion coils 25'. The expansion coils 44 have no thermal contact with the inclined sheet 38 but are spaced and insulated therefrom. The tanks 40, 41 and 42 have spaced vertical heat transfer ice guiding pins 45, 46 and 47, respectively, disposed at the central longitudinal axis of the tanks. These pins have their upper ends secured to and in thermal contact with the cover 39, and their lower ends spaced from the bottoms of the tanks. In connection with the tanks 40, 41 and 42, the freezing action is applied to the bottoms of the sides of the tanks, as explained in connection with the preceding freezing action, and after the ice is formed and the freezing action is stopped, the ice will melt, and the guide pins will retain the ice centered in the tanks, so that it will properly float therein and remain spaced from the sides of the tank. It is thus seen that the refrigerating means within the double-walled top 14 will chill the compartment A from the top while the refrigerating means within the double-walled bracket 37 will chill the compartment A from the bottom, both refrigerating means also serving to chill the interior of the casing 10.

The numeral 48 designates a heat-insulated cold or sub-freezing chamber or compartment, which is mounted upon the back 12 and spaced from the sides and front of the casing 10. This compartment affords spaces or passages 48', upon its opposite sides to receive baskets 49' or the like, removably mounted upon supports 50'. These baskets are employed to hold perishable food products to be retained at ordinary refrig-

eration temperatures. The cold or sub-freezing compartment has a separate cold storage chamber 49 and a separate ice cube chamber 50. The compartment or chamber 49 is closed on all sides excepting at its front, at which it has an opening, covered by a door 52. The compartment 50 is closed on all sides except in its front, at which it has an opening, covered by a door 53. There is a space 54 at the bottom of the casing 10 beneath the compartment 48, and this space receives a basket 54', mounted upon supports 55'. A shelf 56' forms the top of the compartment 48, and this shelf is spaced from all walls of the casing 10, except in the back. The compartment 48 is double-walled and holds heat insulating material. Disposed within the upper end of the compartment, between its top and the top of the chamber 49, is refrigerating means, including a plurality of tanks 55, substantially identical with the tanks 18^a and serving to hold brine, or other liquid freezable medium. These tanks are hermetically sealed and have the air spaces above the liquid. These tanks also have heat-transfer ice guiding pins 56, corresponding to the pins 26, for the same purpose, and the pins 56 are in thermal contact with the bottoms of the tanks 55, which bottoms are in thermal contact with the inner wall 57. Expansion elements or coils 58, corresponding to the expansion coils 25', are provided for the tanks 55, and are in thermal contact with the lower half of the sides of these tanks. The tanks 55 are spaced from the shelf 56', and heat insulating material 59 is arranged between these parts, which also extends within the front and bottom of the double-walled compartment 48. Arranged between the chambers 49 and 50 are tanks 60, substantially identical with the tanks 18^a for holding a liquid freezable medium, such as brine or the like, and having air spaces in their tops. The expansion elements or coils 61, correspond to the elements 25^a, are in thermal contact with the lower half of the sides of the tanks 60. Arranged within the tanks 60 are vertical heat-transfer ice guiding pins 62, corresponding to the pins 26, and having the same function. The pins 62 are in thermal contact with the top 63 of the tanks and also in thermal contact with the bottoms 64 of the tanks. At the back of the chamber 49 are tanks 65, identical with the tanks 29 and having expansion coils 66, identical with the expansion coils 36, and heat exchange ice guide pins 67 identical with the pins 35. The tanks 65 are in thermal contact with the inner back wall 68 of the chamber 49, which wall forms a part of the tanks, but the tanks are spaced from the outer wall 27^a and are insulated therefrom by the insulating material 24, as shown. Both sets of tanks 55 and 60 and the tanks 65 will chill the chamber 49, while the tanks 60 will also chill the chamber 50. Since the tanks 55 and 60 are employed to produce a sub-freezing temperature they will hold a liquid freezable medium, such as brine or the like. The chamber 50 is heat insulated from the space 54, as shown.

As shown in Figure 5, the lower turns 61^a of the coils 61 are connected in series, and the intake turn 61^a is connected in series with the lowermost coil 66, connected with a pipe 67. The outlet turn 61^a is connected in series with the intake turn 62^a of the upper turns. These upper turns 62^a are connected in series and the outlet turn 62^a is connected with a pipe 68, connected with the second coil 66 from the bottom. The second and third coils 66 from the bottom are connected in

series, and the third coil 36 from the bottom is connected with the intake turn 58^a of the lower set of turns 58^a. The outlet turn 58^a is connected with the intake turn 59^a of the upper set of turns 59^a, and the outlet turn 59^a is connected with a pipe 69, connected with the lowermost coil 36. The first, second, third, fourth and fifth coils 36 from the bottom are connected in series and the fifth coil 36 from the bottom is connected in series with the lowermost turn 44^a of the coil 44 of the tank 42. The uppermost or outlet coil 44^a is connected in series with the lower turn 44^b of the coil 44 of the tank 41, and the uppermost turn 44^b is connected with a pipe 68^a, connected with the sixth coil 36 from the bottom. This coil 36 is connected with the turn 44^c of the coil 44 of the tank 41. The turn 44^c is connected with a pipe 71, connected with the seventh coil 36 from the bottom. The seventh, eighth, ninth and tenth coils 36 from the bottom are connected in series, and the uppermost coil 36 is connected with a pipe 72, connected with the intake turn 25^b of a lower set of turns 25^b of the coils 25^b. The outlet turn 25^b is connected with the upper inlet turn 25^c of an upper set of turns, and the outlet turn 25^c is connected with a pipe 73, having a liquid trap 73'. The pipe 73 is connected with the intake side of a compressor 74, the outlet side of which is connected with a pipe 75, discharging into a radiator or condenser 76. The pipe 77 connects with the discharge end of the condenser and is connected with the pipe 67, and a restrictor valve 78 is connected in the pipe 77.

The compressor 74 is driven by a motor 79. This motor is connected in a circuit including lead wires 80 and 81. A thermostatic switch 82 is connected in the wire 81. A clock controlled switch 83 is connected in the wire 80 and this clock controlled switch may be cut out or into circuit by a switch 84. A manually operated switch 85 is also connected in the wire 80. It is thus seen that by opening the switch 85 and closing the switch 84 that the clock controlled switch will then be connected in the wire 80. This clock controlled switch may close the circuit at the 45 clock, intermittently, or continuously, during any selected portion of the day, or throughout the entire day. When it is desired not to employ a time controlled means to close the circuit at one point, switch 84 is opened and the circuit may be 50 manually closed by the switch 85. The thermostatic switch 82 closes the circuit at a second point. As more clearly shown in Figure 1, the thermostatic switch 82 is located between one tank 29 and the tank 42. This thermostatic switch 55 is in thermal contact with either or both tanks, and is arranged at or slightly above the maximum water level of the tank or tanks. The thermostatic switch remains closed until the temperature applied thereto reaches 32° minus, at 60 which time it will open and remain open until the temperature again rises above 32° minus at which time it will close the circuit.

The operation is as follows:

The compressor 74 withdraws the vaporized 65 refrigerant from the outlet turn 25^c through the pipe 73, converts it into a liquid and passes it into the condenser or radiator 76. From this condenser the liquefied refrigerant passes through the restrictor valve 78 and enters the pipe 67 and passes in succession through the lowermost coil 66 and the turns 61^a, and through the turns 62^a, in which expansion occurs and some of the liquid is vaporized. The liquid refrigerant and vapor 70 then passes through the pipe 68, the second and

third coils 36 from the bottom, the turns 58^a and the turns 59^a, into which further expansion and vaporization occurs. The resultant liquid and gas then passes in succession through the first, second, third, fourth and fifth coils 36 from the bottom, in which further expansion and vaporization occur. The liquid and gas then pass through the turns 44^a, the turns 44^b and the sixth coil 36 from the bottom, wherein further expansion and vaporization occur. The liquid and gas then pass through the pipe 70^a, turn 44^c and pipe 71 and the seventh, eighth, ninth and tenth coils 36 from the bottom, wherein further expansion and vaporization occur. The liquid and gas then pass through the pipe 72, through the turns 25^b, and the turns 25^c and to the pipe 73, whereby further vaporization and expansion occur. When the vapor enters the pipe 73 the cycle of operation is repeated. The liquid trap 73' prevents any of the liquid returning to the compressor. It is thus seen that the liquid and vapor when passing through the several turns, coils, pipes, either travel horizontally or upwardly, or the arrangement may be such that they will travel upwardly continuously.

While I have shown the refrigerant as supplied from a unit including a compressor, the refrigerant may also be supplied in the form of a gas, from a unit as is employed in the Electrolux refrigerator, and in which a flame or heat is used to produce the gaseous refrigerant.

Since the refrigerating means for the chambers 49 and 50 are within the heat insulated compartment, they do not materially chill the interior of the casing 10. This prevents the sub-freezing temperature from occurring within the casing 10, exteriorly of the sub-freezing compartment, so that the food products within the casing are not dehydrated. The interior of the casing is chilled principally by the refrigerating means including the tanks 18^a, tanks 29, tanks 65 and tanks 40, 41 and 42, without liability of dehydrating the food products, as the refrigerating mechanism will be stopped at about the time that all of the water in these tanks is completely frozen. The combined volume of the ice produced is sufficient to keep the interior of the casing suitably chilled for a considerable period, after the compressor stops. The chilled air produced at the top of the casing descends, while the warmer air rises, thus producing suitable circulation within the casing, about the shelf and compartment 48. The passages 48' provide suitable space for this circulation.

In Figures 6 and 7, I have illustrated the method of freezing the water or other freezable liquid medium, in the V-shaped tanks. When the apparatus is started, the refrigerating mechanism runs until all the water is completely frozen in the tank 20, Figures 6 and 7, to provide a cake of ice 20^c, contacting with the sides 21^b, ends 21, bottom 25, and guide pins 26. When the water is thus substantially completely frozen within this tank and within the other tanks, the refrigerating mechanism is rendered idle by stopping the action of the compressor, and the thermal contact between the ice and these adjacent parts, causes the ice to melt adjacent to such parts, and the ice is partly melted. This frees the ice from the walls of the tank, and the ice floats and rises. The ice also melts adjacent to the guide pins. These guide pins now guide the ice in its floating movement and retain the ice spaced from the sides and ends of the tank. If the ice contacted with one side, capillary

action would cause the ice to adhere to such side and slide up the same. The pins 26 thus guide the ice from the sides 21^b and the coils 25^a. The ice is allowed to partly melt, while the refrigerating mechanism remains inactive, until a thin layer of water 20^e surrounds the floating ice and parts of the tank. This thin layer of water may vary in thickness, but it is preferred that it should be about one fourth of an inch in cross section. The thinner the layer of ice 20^e, the quicker and more economically the freezing action may be effected. A very thin layer freezes almost instantly. When the thin layer of water 20^e is provided, the compressor starts and the freezing starts at the outer face of the layer 20^e adjacent to its bottom edge. This freezing continues inwardly, and slows down and becomes more difficult as the thickness of the ice between the wall 20^b and the water increases. The freezing action is continued until the layer is completely frozen and then the compressor is stopped. The freezing action also starts at the bottom of the layer and continues upwardly, so that the top layer is frozen last. This prevents the freezing action from bursting the tank. When the layer of water finishes freezing at the top, it loses its ability to absorb the sub-freezing temperatures, and therefore the thermostatic switch is set to open at this time, to stop the compressor. The unfrozen water at the top serves as a shield and will absorb any sub-freezing temperatures until the water is completely frozen. In this way, the food products can be subjected to the maximum cooling temperatures, without liability of being frozen or dehydrated. The cycle of operation is repeated. The same action occurs in all of the V-shaped tanks. Substantially the same action occurs in the back tanks 29 and 65, except that the pins 67 guide the ice into contact with the inner heat exchange wall 27, and produce a layer of water 27^a, between the wall 29 and the ice. When the refrigerating mechanism is again rendered active, the layer of water 27^a is frozen, as explained.

In each instance, when the previously formed ice partly melts within the tank, it is guided from the freezing wall of the tank, so that a thin layer of water is produced at such wall, and when the refrigerating mechanism again starts, the wall will freeze the thin layer of water. In this manner, a thin layer of water is successively frozen in each tank.

By providing a large number of thin tanks, the combined volume of the ice produced is sufficient to properly chill the interior of the refrigerator casing. The arrangement also produces a large number of thin water layers, which are frozen in succession, thus increasing the efficiency of the apparatus. This avoids the necessity of freezing through thick ice, except when first starting the refrigerator to completely freeze the water in the tanks.

The apparatus may be operated without the thermostatic switch. In this event, the clock switch would be disconnected from the circuit and the circuit opened and closed, at intervals by the switch 85. When it is desired to have the operation automatic, the thermostatic switch is employed, while the switch 85 may be closed and the switch 84 opened. When the ice partly melts in the tanks, the thermostatic switch will close and the compressor will be driven, until the water in the tanks has again completely frozen, at which time the thermostatic switch will again open and the compressor will stop. This auto-

matic operation may occur during a selected part of the day when current is cheap or available, and when this is desired the switch 85 is opened and the switch 84 closed. The thermostatic switch will open and close the motor circuit, as explained, and the clock switch will close the circuit at another point at the beginning of a selected portion of the day and again open the circuit at the end of such selected portion.

The food products upon the shelf 39 are in thermal contact therewith and therefore in thermal contact with the ice through the medium of the tanks 40, 41 and 42. The shelf 39 may have a temperature of 32° plus but not a temperature below this. There is therefore no necessity to have the refrigerating mechanism produce an exposed temperature below 32° plus, as must be done with the ordinary mechanical refrigerator, wherein the exposed temperature is always below 32° during operation, for otherwise the compressor would never operate when the coil is covered with frost. The frost is at least 32°, but is not of sufficient volume to properly chill the box and therefore the compressor must continue to operate to properly chill the box.

In connection with all parts of the refrigerator where heat exchange is to be effected, such parts are to be formed of metal or other suitable heat transfer material.

In Figures 10 and 11 I have shown a sub-freezing box for holding frozen food products. This box is preferably rectangular, vertical and includes an inner casing 86 and an outer casing 87, forming a double-walled construction. The double-walled construction holds heat insulating material 88. Access is had to the interior of the inner casing 86 at the top only, through an opening 89, to be closed by a removable cover 90.

Surrounding the casing 86 are superposed horizontal sets of tanks 91, corresponding to the tanks 29. The walls of the casing 86 form the inner sides of these tanks. The tanks 91 are therefore in thermal contact with the casing 86. The tanks 91 are hermetically sealed, and are partly filled with a liquid freezable medium 92, such as brine or the like. There is an air space 93 at the top of each tank. Each tank has an ice guide pin 94, corresponding to the pin 35, and inclined upwardly toward the wall of the casing 86. Surrounding the wall portions of each set of tanks is a refrigerating coil 95, including a lower turn 95^a and an upper turn 95^b. The coil is in thermal contact with the outer sides of the tanks 91, and does not extend above the lower half of the tanks.

Arranged beneath the bottom 96 of the casing 86 are tanks 97 corresponding to the tanks 20, and in thermal contact with the bottom 96. 98 are vertical ice guide pins. The tanks 97 are hermetically sealed and are partly filled with brine or the like, and have air spaces 99 at their tops. A refrigerating coil 100 surrounds the lower portion of each tank 97, in thermal contact therewith, and does not extend above the lower half of the tank. Each coil 100 includes a lower turn 100^a and an upper turn 100^b. The lower turns 100^a form a horizontal group and are all connected in series like the coils 61^a, Figure 5, and the upper turns 100^b form a horizontal group and are connected in series like the turns 62^a.

The lower intake turn 100^a is connected with a pipe 101, having a restrictor valve 102 connected therein. The pipe 101 is connected with the outlet end of a condenser or radiator 103, connected with a pipe 104. This pipe is connected with the

discharge side of a compressor 105, driven by a motor 106 or the like. The outlet turn 100^a is connected with the intake turn 100^b, and the outlet turn 100^b is connected with the lower turn 95^a of the next coil 95. The upper turn 95^b of each coil is connected with the lower turn 95^a of the coil above it. All of the coils 95 are therefore connected in series. The upper turn 95^b of the uppermost coil 95 is connected with a pipe 107, having a liquid trap 108 connected therein. The pipe 107 is connected with the intake side of the compressor.

It is thus seen that the liquid refrigerant passing through the pipe 101 will first pass through the lower group of turns 100^a, then through the upper group of turns 100^b, and then through the several coils 95 in succession. Expansion and vaporization occur in these coils. The vapor is returned through the pipe 107 to the compressor. The liquid and gas therefore travel horizontally and upwardly through the various coils. The groups of turns may be inclined outwardly, and the coils 95 may be inclined upwardly, whereby the liquid and gas will travel upwardly continuously when passing through the coils. The apparatus may be used with or without the thermostatic switch or with or without the clock switch. The operation of the apparatus is so similar to that of the first part of the invention that no further explanation is thought to be necessary, except to state that ice is formed in each tank, allowed to partly melt and float to provide the thin layer of brine which is then frozen.

In Figure 12, I have shown a further modification of the invention. In this figure, the numeral 108 designates an insulating casing, in the lower portion of which are mounted tanks 109, corresponding to the tanks 20 and having ice guide pins 110, corresponding to the pins 26. The tanks 109 are hermetically sealed and partly filled with water, with air spaces at the tops of the tanks. Means are provided to form passages 111, surrounding the lower portion of the tanks 109, and in thermal contact therewith to receive a gaseous refrigerant from a unit such as is used by the Electrolux. These several passages which surround the tanks 109 are connected in series. Means are provided to form passages 112, surrounding the upper portions of the tanks 109, and in thermal contact therewith. These passages 112 may also be connected in series and serve to hold a fluid which will freeze at a lower freezing point than water, such as brine, air or the like. Arranged above the tanks 109 are corresponding tanks 113, for receiving water and having the air spaces at their tops and ice guide pin 114. Means are provided for affording passages 115 at the lower portions of the tanks 113, and in thermal contact therewith, to receive a gaseous refrigerant from a unit like the Electrolux. The passages 115 are connected in series and the passages 115 are also connected in series with the passages 111. Means are provided to afford passages 116 surrounding the upper portions of the tanks 113, and in thermal contact therewith, to receive a fluid medium which will freeze at a lower freezing point than water, such as brine, air or the like. The passages 116 are connected in series with each other and in series with the passages 112. The fluid first passes through the passages 112 and then through the passages 116 and then to the cooling coil of an air conditioning unit refrigerator or the like. When the water is completely frozen in the tanks 109 and 113 a thermostat will turn off the flame or heat,

In Figure 15, the same tanks 109 are employed and the same tanks 113, except that the tanks 113 correspond in number to the tanks 109 and are arranged in alignment therewith. The same ice guide pins are provided. The tanks 109 have the same passages 112 for the fluid to be chilled, such as brine, air, and the tanks 113 have the passages 116 to receive the fluid, such as brine or air, and these passages are connected in the same manner as described in connection with Figure 12. Coils 117 surround the lower portions of the tanks 109 in thermal contact therewith, and receive the refrigerant from a unit including a compressor. Corresponding coils 118 surround the lower ends of the tanks 113, and in thermal contact therewith. The coils 117 are connected in series with each other and the coils 118 are connected in series with each other and in series with the coils 117. In this form of the invention, when the water is completely frozen in the tanks, the thermostat will stop the action of the compressor.

It is to be understood that the forms of my invention herewith shown and described are to be taken as preferred examples of the same and that various changes in the shape, size, and arrangement of parts may be resorted to without departing from the spirit of my invention or the scope of the subjoined claims.

Having thus described my invention, what I claim is:

1. In a refrigerator, a casing having a heat transfer wall, a downwardly tapered liquid freezable medium holding tank having a part thereof in thermal contact with the wall, said tank having opposed downwardly converging walls, upstanding ice guide pins for the tank and disposed within the tank and arranged between the downwardly converging walls, a refrigerating element arranged adjacent to the tank, and means to retain the ice between the downwardly converging walls.

2. In a refrigerator, a casing having a heat transfer wall, a plurality of downwardly tapering tanks having their bottoms in thermal contact with the wall and adapted for holding a liquid freezable medium, each tank having opposed downwardly converging sides, substantially vertical guide pins arranged within the tanks between the downwardly converging sides, refrigerating means disposed adjacent to the bottoms of the tanks, and means to retain the ice between the downwardly converging sides of each tank.

3. In a refrigerator, a downwardly tapering tank for holding a liquid freezable medium, said tank including opposed downwardly converging sides, a refrigerating element disposed exteriorly of the tank adjacent to its bottom and not extending upwardly for substantially more than one half of the height of the tank, and substantially vertical ice guide means within the tank and arranged between the downwardly converging sides and in thermal contact with the tank, and means to retain the ice between the downwardly converging sides.

4. In a refrigerator, a casing including a double wall top having an inner heat transfer wall, liquid freezable medium holding tanks disposed within the double wall top and in thermal contact with the inner heat transfer wall, refrigerating means arranged within the double wall top exteriorly of the tanks and adjacent to their bottoms, ice guide means arranged within each tank, a double wall shelf arranged within the casing beneath

and spaced from said top, said double wall shelf including an upper heat transfer wall, a plurality of liquid freezable medium holding tanks arranged within the double wall shelf and in thermal contact with the upper wall, refrigerating means arranged within the double wall shelf and disposed adjacent to the bottoms of the last named tanks, and ice guide means arranged within the last named tanks.

5. In a refrigerator, a double wall casing, tanks arranged within the double wall for holding a liquid freezable medium, refrigerating means for the tanks and arranged within the double wall casing, a double wall shelf arranged within the casing and providing a passage for the circulation of air within the casing, said shelf having an upper heat conducting wall, tanks arranged within the double wall shelf for holding a liquid freezable medium, refrigerating means within the double wall shelf and disposed adjacent to the last named tanks, a heat insulated compartment mounted within the casing and providing a passage for the circulation of air within the casing, said compartment including a cold chamber and an ice cube chamber, a plurality of tanks for holding a liquid freezable medium disposed within the heat insulated compartment at the top of the cold chamber, refrigerating means for the last named tanks, a plurality of tanks for holding a liquid freezable medium arranged within the heat insulated compartment and disposed between the cold compartment and the ice cube compartment, and refrigerating means for the last named tanks.

6. In a refrigerator, a heat insulated compartment having a cold chamber and an ice cube chamber, a plurality of tanks for holding a liquid freezable medium arranged within the heat insulated compartment and in thermal contact with the wall of the cold chamber, refrigerating means for the tanks and disposed adjacent to their bottoms, ice guide means arranged within each tank, a plurality of tanks for holding a liquid freezable medium and arranged within the heat insulated compartment and disposed between the wall of the cold chamber and the wall of the ice cube chamber and in thermal contact therewith, refrigerating means for the last named tanks, and ice guide means within each of the last named tanks.

7. In a refrigerator, a casing including a double wall top having an inner heat transfer wall and a double wall back having an inner heat transfer wall, tanks for holding a liquid freezable medium in thermal contact with the top heat transfer wall, refrigerating means for the tanks, tanks for holding a liquid freezable medium in thermal contact with the back heat transfer wall, refrigerating means for the last named tanks, a heat insulated compartment arranged within the casing and forming an air circulating passage with the casing, tanks for holding a liquid freezable medium and arranged within the heat insulated compartment, and refrigerating means for the last named tanks.

8. In a refrigerator, a casing, tanks for holding a liquid freezable medium disposed adjacent to the top of the casing, refrigerating means for the tanks, a shelf arranged within the casing next to the top, tanks for holding a liquid freezable medium and in thermal contact with the shelf, refrigerating means for the last named tanks, a heat insulated compartment within the casing beneath the shelf, tanks for holding a liquid freezable medium arranged within the heat in-

sulated compartment, and refrigerating means for the last named tanks.

9. In a refrigerator, a casing, tanks for holding a liquid freezable medium disposed adjacent to the top of the casing, refrigerating means for the tanks, a shelf arranged within the casing beneath and spaced from the top and spaced from the sides of the casing, tanks for holding a liquid freezable medium arranged in thermal contact with the shelf, refrigerating means for the last named tanks, a heat insulated compartment within the lower portion of the casing beneath the shelf and spaced from the shelf and from the bottom of the casing to provide a bottom passage and from the sides of the casing to provide side passages, tanks for holding a liquid freezable medium arranged within the heat insulated compartment, a receptacle removably inserted in the bottom passage, and receptacles removably inserted within the side passages.

10. In a refrigerator, a casing, a double wall shelf arranged within the casing and having an upper heat transfer wall and forming with the casing an air circulating passage, tanks for holding a liquid freezable medium arranged within the double wall shelf and in thermal contact with the upper transfer wall, expansion elements arranged within the double wall shelf adjacent to the tanks, and heat insulating means for the tanks arranged beneath the same.

11. In a refrigerator, a casing having a double wall top including an inner heat transfer wall and a double wall back having an inner heat transfer wall, tanks for holding a liquid freezable

35 medium mounted within the double wall top and in thermal contact with the inner heat transfer wall, expansion coils within the double wall top and disposed adjacent to the tanks, tanks for holding a liquid freezable medium and arranged within the double wall back and in thermal contact with the heat transfer back wall, expansion coils for the last named tanks, a double wall shelf including an upper heat transfer wall, tanks for holding a liquid freezable medium and 45 mounted within the double wall shelf and in thermal contact with the heat transfer shelf wall, expansion coils for the last named tanks arranged within the double wall shelf, a heat insulated compartment within the casing including a cold chamber and an ice cube chamber, the cold chamber having heat transfer opposed walls and the ice cube chamber having a heat transfer wall, tanks for holding a liquid freezable medium and arranged within the heat insulated

50 compartment and in thermal contact with the cold chamber wall, expansion coils for the last named tanks, tanks for holding a liquid freezable medium disposed between the wall of the cold chamber and the wall of the ice cube chamber and in thermal contact therewith, and expansion coils for the last named tanks.

12. In a refrigerator, a casing having a chamber including a heat exchange wall, means arranged upon the outer side of the heat exchange

65 wall to form a tank and including an inclined freezing wall in thermal contact with the heat exchange wall, the tank holding a liquid freezable medium, inclined means arranged within the tank to guide the floating ice from the inclined wall and into contact with the heat exchange wall, and means to apply a freezing action to the inclined wall.

13. In apparatus for holding frozen foods or the like, a casing closed at its sides and bottom 70 and open at its top, a cover for closing the open

top, water holding tanks disposed at different elevations at the side of the casing, water holding tanks disposed at the bottom of the casing, refrigerating elements arranged adjacent to the lower ends of the water holding tanks, and ice guide means within the water holding tanks.

14. In apparatus for holding frozen foods or the like, a casing having its side and bottom closed and its top provided with an opening, a cover for the opening, vertically tapered tanks adjacent to the sides of the casing and arranged in superposed relation, vertically tapered tanks arranged adjacent to the bottom of the casing, ice guide means within the tanks, and refrigerating elements arranged adjacent to the bottom portions of the tank.

15. In apparatus for holding frozen foods or the like, a substantially vertical casing having its side and bottom closed and having an opening in its top, a cover for the opening, vertically tapered water holding tanks in thermal contact with the side of the casing, vertically inclined ice guide pins arranged within the water holding tanks and having their upper ends extending toward the sides of the casing, and refrigerating elements adjacent to the lower portions of the water holding tanks.

16. In apparatus of the character described, a plurality of vertically tapered water holding tanks, ice guide means within the tanks, means arranged adjacent to the lower portions of the tanks for forming passages for holding a refrigerant, and means arranged adjacent to the upper portions of the tanks for forming a passage for holding a chilling fluid.

17. In apparatus of the character described, an insulating casing, a lower group of vertically tapered water holding tanks arranged within the casing, ice guide means within the tanks, an upper group of vertically tapered water holding tanks arranged within the casing, ice guide means within the upper group of tanks, means arranged adjacent to the lower ends of all of the water holding tanks and forming a passage for receiving a refrigerant, and means arranged adjacent to the upper ends of all of said tanks for receiving a chilling fluid.

18. In apparatus of the character described, a heat insulating casing, a lower horizontal group of vertical tapered tanks arranged within the casing and forming spaces between them, means surrounding the lower end portions of the tanks and extending into the spaces between the tanks for forming a passage for receiving a refrigerant, means arranged adjacent to the upper end portion of the tanks and extending into the spaces between them for forming a passage for holding a chilling fluid, an upper horizontal group of water holding tanks arranged within the casing, means arranged adjacent to the lower end portions of the upper tanks and extending into the spaces between them for forming a passage having communication with the passage near the lower end of the first named tanks, means arranged adjacent to the upper ends of the upper tanks and extending into the spaces for holding a chilling fluid and having communication with the passage adjacent to the upper end of the first named tanks.

19. In apparatus of the character described, an insulating casing, a group of vertically tapered water holding tanks arranged within the casing, refrigerating coils in thermal contact with the lower ends of the tanks, and means disposed in thermal contact with the upper ends of the tanks

and in thermal contact therewith and forming a passage for holding a chilling fluid.

20. In a refrigerator, a case having a food compartment, a tank to chill the air within the food compartment, said tank having a chamber tapered in cross section and decreasing downwardly toward its bottom, said chamber holding a liquid freezable medium, a refrigerating element disposed adjacent to the bottom of the tank, ice guide means within the downwardly tapered chamber for guiding the ice when it floats, and means to retain the ice within the downwardly tapered chamber.

21. In a refrigerator, a case, refrigerating mechanism for the case including a tank having a downwardly tapered chamber for holding a liquid freezable medium, upstanding ice guide means within the downwardly tapered chamber, and a refrigerating element disposed exteriorly of and adjacent to the tank, and means to retain the ice within the downwardly tapered chamber.

22. In a refrigerator, a case, refrigerating mechanism for the case including a plurality of tanks having downwardly tapered chambers for holding a liquid freezable medium, upstanding ice guide pins disposed within the downwardly tapered chambers, refrigerating means disposed outwardly of the tanks and adjacent thereto, and means to retain the ice within each downwardly tapered chamber.

23. In a refrigerator, a case, refrigerating mechanism for the case including a plurality of separate tanks arranged in close relation, each tank having a downwardly tapered chamber to hold a liquid freezable medium, substantially vertical ice guide pins within the downwardly tapered chambers, means to apply a freezing action to each chamber, and means to retain the ice within each downwardly tapered chamber.

24. In a refrigerator, a casing having a food compartment, a downwardly tapered liquid freezing medium holding tank to chill the air within the food compartment, said tank having opposed downwardly converging walls, an upstanding ice guide pin arranged within the tank between the downwardly converging walls, a refrigerating element adjacent to the tank, and means to retain the ice between the downwardly converging walls.

25. In a refrigerator, a heat insulated case having a food compartment, substantially horizontal long narrow downwardly tapering tanks for holding a liquid freezable medium arranged within the heat insulated case and exteriorly of the food compartment for chilling the air within the food compartment, the combined volume of the tanks being sufficiently large to hold enough ice to retain the food products refrigerated for a substantial period, means for applying a freezing action to the lower reduced portion of each tank, a heat insulated compartment arranged within the case, tanks for holding a liquid freezable medium arranged within the heat insulated compartment, and refrigerating means for the last named tanks.

26. In a refrigerator, a heat insulated case having a food compartment, substantially horizontal long narrow downwardly tapering tanks for holding a liquid freezable medium arranged within the heat insulated case and exteriorly of the food compartment for chilling the air within the food compartment, at least some of the tanks being arranged near the top of the food compartment, a shelf arranged within the food compartment and spaced from the top of the food compartment, at least some of the tanks being

arranged above the shelf, tanks arranged beneath the shelf and in thermal contact therewith for holding a liquid freezable medium, refrigerating means for the last named tanks, insulating means covering the lower portions of the last named tanks, a heat insulated compartment within the case, tanks for holding the liquid freezable medium arranged within the heat insulated compartment, and refrigerating means for the last named tanks.

27. In a refrigerator, a heat insulated case having a food compartment, substantially horizontal long narrow downwardly tapering tanks arranged within the case exteriorly of the food compartment for holding a liquid freezable medium to chill the air in the food compartment, means for applying a freezing action to the reduced lower portion of each tank, at least some of the tanks being arranged adjacent to the top of the food compartment, a shelf arranged within the food compartment and spaced from its top, substantially horizontal long narrow downwardly tapering tanks arranged beneath the shelf in thermal contact therewith for holding a liquid freezable medium, means to apply a freezing action to the lower portions of the last named tanks, and heat insulating means covering the last named tanks beneath the shelf.

28. In a refrigerator, a heat insulated case having a food compartment, a shelf arranged within the food compartment and spaced from the top of the food compartment, substantially horizontal long narrow downwardly tapering tanks for holding a liquid freezable medium arranged within the case exteriorly of the food compartment for chilling the air within the food compartment, at least some of the tanks being arranged above the shelf, means for applying a freezing action to the lower portion of each tank, substantially horizontal long narrow downwardly tapering tanks arranged beneath the shelf in substantial thermal contact therewith for holding a liquid freezable medium, means for applying a freezing action to the lower portion of each last named tank, insulating means for covering the lower portions of the last named tanks, a heat insulated compartment within the case, substantially horizontal long narrow downwardly tapering tanks within the heat insulated compartment, and means to apply a freezing action to the lower portion of the last named tanks.

29. In a refrigerator, a heat insulated case having a food compartment, substantially hori-

- zontal long narrow downwardly tapering tanks for holding a liquid freezable medium arranged within the heat insulated case exteriorly of the food compartment for chilling the air within the food compartment, the tanks extending substantially throughout the horizontal dimension of the food compartment, the tanks being arranged in close relation, the combined volume of the tanks being sufficiently large to hold enough ice to retain the products refrigerated for a substantial period, and means for applying a freezing action to the lower portion of each tank.
30. In a refrigerator, a heat insulated case having a food compartment, substantially horizontal long narrow tanks within the case for holding a liquid freezable medium to chill the air within the food compartment, the tanks being arranged in close relation and substantially covering at least a portion of one face of the compartment, and means to intermittently apply a freezing action to the lower portion of each tank for producing thin layers of ice and prolonging the intervals between the freezing action sufficiently to permit the thin layers to melt and free the ice from the inner face of the tank so that the ice may float in the water in the tank.

HENRY M. HERBENER.
